FOUNTAIN PEN

Homer T. Green, Milton, Wis., assignor to The Parker
Pen Company, Janesville, Wis.

Filed Apr. 22, 1970, Ser. No. 22,553

Term of patent 14 years

Int. Cl. D19—06

U.S. Cl. D74—17

FIG.1

FIG.3

FIG.2

FIG.4

FIG.5

FIG.7

FIG.6

FIG.8

FIG.9

FIG. 1 is a top plan view of a fountain pen illustrating my new design;

FIG. 2 is a front elevational view;

FIG. 3 is a side elevational view from the right of FIG. 2;

FIG. 4 is a rear view;

FIG. 5 is a bottom view;

FIG. 6 is another front elevational view of the fountain pen as it appears in use;

FIG. 7 is a side elevational view from the right of FIG. 6;

FIG. 8 is a rear view; and

FIG. 9 is a bottom view taken along the line 9-9 of FIG. 6 looking in the direction indicated by the arrows and having the clip removed.

I claim:

The ornamental design for a fountain pen, as shown and described.
